UNITED STATES PATENT OFFICE

148,480

DESIGN FOR A MOTION-PICTURE PROJECTOR

Lewis H. Moomaw, Great Neck, N. Y., assignor to
De Jur-Amseco Corporation, Long Island City,
N. Y., a corporation of New York

Application March 6, 1947, Serial No. 137,401

Term of patent 7 years

(Cl. D61—1)

To all whom it may concern:

Be it known that I, Lewis H. Moomaw, a citizen of the United States and a resident of Great Neck, in the county of Nassau and State of New York, have invented a new, original, and ornamental Design for a Motion-Picture Projector, of which the following is a specification, reference being had to the accompanying drawings, forming a part thereof, in which:

Fig. 1 is a three-quarter perspective view taken from the right side rear of a motion-picture projector, showing my new design;

Fig. 2 is a perspective view taken from the left side front; and

Fig. 3 is a perspective view taken from the left side rear.

I claim:
The ornamental design for a motion-picture projector, as shown.

LEWIS H. MOOMAW.
